(57) **CLAIM**

The ornamental design for a slider assembly, as shown and described.

DESCRIPTION

FIG. 1 is a perspective view of a first embodiment of a slider assembly showing our new design; FIG. 2 is a front view of FIG. 1; FIG. 3 is a back view of FIG. 1; FIG. 4 is a right-side view of FIG. 1; FIG. 5 is a left-side view of FIG. 1; FIG. 6 is a top plan view of FIG. 1; FIG. 7 is a bottom plan view of FIG. 1; FIG. 8 is a perspective view of the slider of FIG. 1 with the button in a disengaged position; FIG. 9 is a perspective view of the slider of FIG. 1 with the button in an intermediate position; FIG. 10 is a perspective view of the slider of FIG. 1 with the button in an engaged position; FIG. 11 is a perspective view of a second embodiment of a slider assembly showing our new design; FIG. 12 is a front view of FIG. 11; FIG. 13 is a back view of FIG. 11; FIG. 14 is a right-side view of FIG. 11; FIG. 15 is a left-side view of FIG. 11; FIG. 16 is a top plan view of FIG. 11; and, FIG. 17 is a bottom plan view of FIG. 11. The broken lines in the drawings depict portions of the slider assembly that form no part of the claimed design.

1 Claim, 13 Drawing Sheets
